UNITED STATES PATENT OFFICE.

HENRY E. OLIVER, OF BIRMINGHAM, ALABAMA, ASSIGNOR OF ONE-HALF TO JOHN V. MORRIS, OF BIRMINGHAM, ALABAMA.

BONUS-DETERMINING DEVICE.

1,104,069.

Specification of Letters Patent. Patented July 21, 1914.

Application filed June 2, 1913. Serial No. 771,344.

To all whom it may concern:

Be it known that I, HENRY E. OLIVER, a citizen of the United States of America, residing at Birmingham, in the county of Jefferson and State of Alabama, have invented 5 certain new and useful Improvements in Bonus-Determining Devices, of which the following is a specification.

My invention relates to certain new and 10 useful improvements in machines designed to stimulate business and which are dependent upon the skill of the customer for determining the amount of bonus which he shall receive in merchandise with each purchase.

15 The object of my invention is to design a machine provided with an elongated coin slot so that the customer may select any point in the slot to drop his coin. The coin passage is interrupted by a small 20 number of carefully arranged cushion pins from which the coins are adapted to rebound into one of the coin receiving pockets but which permit the customer by the skilful manner in which he 25 drops the coin to cause it to fall into the desired pocket which entitles the customer to receive a bonus in addition to the purchase which he contemplates. The pins are so arranged with reference to the slot and the 30 pockets that the customer, who is sufficiently skilful, may succeed in causing his coin to drop into a given pocket by rebounding from pin to pin or to the side of the cabinet, the coin acting like a billiard or a pool ball 35 in responding to definite laws covering its travel. In this respect my invention differs in principle and operation from the machines in which the coin is dropped through a restricted slot and works its way through 40 a number of interposed pins before it falls into the coin pockets, for there the customer has no opportunity to bring into play his skill in selecting the point at which to drop the coin after a careful consideration of its 45 probable action with reference to the pin or pins which he intends it to strike.

50 My invention further comprises the novel details of construction and arrangements of parts which are hereinafter more particularly described and claimed, reference being had to the accompanying drawings, in which:

55 Figure 1 is a front elevation of my invention. Fig. 2 is a top plan view of the same; and Fig. 3 is a vertical cross-sectional view

taken along the line $x-x$ of Fig. 1. Fig. 4 is an enlarged vertical sectional view showing details of the slot and pin construction.

Similar reference numerals refer to similar parts throughout the drawings. 60

In its preferred embodiment, my invention comprises a cabinet provided with a bottom compartment 1 having a rear opening for the insertion and removal of a subdivided coin till 2 and a top slot or opening 3 through which coins fall into the till. 65 Above the compartment 1 the cabinet comprises upright members 4 which receive a vertically disposed glass front or panel 5 which stands close to and parallel with a wooden back panel 6. The panels 5 and 6 are mounted in or connected to the side members 4 and the space between them registers with the slot 3 below. The members 4 are connected at their tops by spaced strips 70 or members 7 and these members are covered by two parallel strips of glass 8 which are spaced about the thickness of a coin apart and which are held firmly clamped in spaced relationship on the top members by metal 75 corner plates 9. These corner plates are securely fastened to the uprights 4 and cover the top corners of the cabinet, having a top retaining pin 25 which is inserted between and serves to hold the glass strips 8 firmly 80 in spaced relationship to form an elongated slot 10, the sides of which are closed by the corner pieces themselves. This slot extends across the major portion of the width of the top. The vertical back panel 6 has fastened 85 therein a set of pins or pegs 11 which are preferably surrounded by cylindrical cushions 12 formed of rubber or other resilient material through which the pins are passed or driven into the panel 6. The lower part 90 of the coin passage formed between the panels 5 and 6 is divided into coin receiving pockets by vertical parallel partitions formed of any suitable material and preferably connected to the panel 6. The central 95 coin receiving pocket 13 is formed by two middle partitions 14 and on each side of this pocket I arrange two wider pockets 15 formed between the partitions 14 and partitions 16. The outside pockets 17 are formed between 100 the partitions 16 and the side walls of the coin passage. These pockets 17 are substantially overhung by deflecting tapering blocks 18 which are connected to the side members 105 and disposed one above each pocket 17. At 110

the upper end of each of the partitions 14 and 16 and at the outer end of each block 18, I mount a resilient member such as one of the cushioned pins 11. A sufficient vertical opening being left between each partition 16 and its adjacent block 18 to permit a coin to spring laterally into the pockets 17. The several pockets, which at their lower ends merge into the opening 3, are normally closed below by a slide bottom 19 which works on a slideway 20 and has an operating stem 21 which projects rearwardly through the cabinet and has a slot 22 therein which receives the free end of a flat spring 23 which holds the slide in its inner position and is fastened to the rear wall of the cabinet. A knob 24 on the outer end of the stem permits it to be retracted and permits all the coins in the several pockets to drop simultaneously into corresponding pockets in the till 3, which pockets are formed by partitions 26 therein.

It will be noted that the several pins 11 and the blocks 18 are so arranged that a coin dropped through the slot 10 can be caused to engage any one of the pins or blocks at the desired angle so that it will rebound therefrom and drop into any one of the coin pockets. It will also be noted that the pins 11 are so disposed and arranged that the customer dropping the coin can calculate with more or less accuracy, depending upon his skill, just what pin or pins or what block 18 the coin should strike and the direction in which it should rebound therefrom in order to fall into the pocket for which he is playing. In this respect the skill required is similar to that required for the game of pool, the coin taking the place of the ball played, the pins and blocks taking the place of the cushions of the pool table, and the player seeking by the point at which the coin is dropped to cause it to rebound from cushion to cushion and to ultimately lodge in the pocket for which he is playing. The dropping of the coin gives it the momentum which the cue gives the pool ball and the selection of the point for dropping the coin determines its angle of rebound from the pin which it first strikes and this in turn governs its subsequent movements.

It being the object of my invention to reward the skill displayed by the customer in dropping the coins, the pins are arranged to make the central pocket 13 the most difficult pocket in which to drop the coin and a bonus of two additional articles is provided for the customer who is skilful enough to lodge his coin in the central pocket. To indicate this the numeral "3" is affixed to or painted on the panel 6 opposite pocket 13. A single article is allotted the coins falling into the wider pockets 15, which are accordingly numbered "1", and one additional article as

a bonus is allotted to coins falling into the extreme side pockets 17, which are accordingly numbered "2".

The glass strips forming the coin slot 10 are selected because the glass cannot be marked to indicate the points at which the coins dropped would most likely earn a bonus, for if such marks were made and coins dropped with respect thereto, it would increase too greatly the percentage of bonuses which the machine is designed to allow as an average. The arrangement of the pins and the size of the pockets can be accurately calculated to give the customers any desired average premium or bonus and inasmuch as each coin always falls in a pocket entitling the customer to at least the article which he intended to purchase, the apparatus operates only to the advantage of the customer in allowing him more than one under certain conditions.

The coin passage way should be vertically so that coins will rebound freely from the pins. Also I prefer the pins to be always so arranged that a coin cannot be dropped directly into a bonus-giving pocket as it increases the interest in the game and the skill required if the coin must take a cushion before it can fall into the middle or outer pockets. The blocks 18 prevent coins dropping directly into the pockets 17 and the pin immediately over the pocket 13 prevents the coin dropping directly into that pocket but yet permits one who is skilful enough to drop his coin on the pin over either partition 14 so that it will drop into the pocket 13. A number of regular shots for the pockets 13 or 17 can be made by dropping a coin from different points against different pins, and these may be varied by changing the arrangement of the pins, but always the gist of my invention lies in so arranging the pins that the fall of the coin can be predetermined by the skill of the operator and not by chance.

Having thus described my invention, what I claim as new and desire to secure by Letters Patent, is:

1. In an apparatus of the character described, a cabinet comprising a wide coin passage way, a series of coin receiving pockets provided at the bottom of said passage way, a top cover for said passage way having therein an elongated coin slot which extends directly over a major portion of the bottom of the coin passage way above said pockets, a transparent front wall for said coin passage way, and pins which project into said coin passage way and are arranged to prevent a coin being dropped directly into any given pocket while permitting the coin to be dropped skilfully to directly strike any one of a number of pins and to rebound therefrom before entering a pocket, substantially as described.

2. In an apparatus of the character described, a cabinet provided with a wide vertical coin passage having its front wall transparent, resilient pins interposed in said passage way and having a predetermined relationship to each other and to coin pockets at the bottom of the passage, a cover over the passage having an elongated slot which extends directly over a number of 10 said pins to permit a coin being skilfully dropped against any pin selected from among those disposed directly under said slot to obtain a predetermined rebound therefrom, and partitions forming pockets 15 to receive coins at the bottom of the passage.
3. In an apparatus of the character described, a cabinet provided with a wide vertical coin passage having substantially parallel side walls and a transparent front wall, 20 resilient pins interposed in said passage way and distributed crosswise thereof in a predetermined relationship to each other and to coin pockets at the bottom of the passage, a top cover over the passage having a slot 25 extending substantially from side to side of the top and being sufficiently elongated to permit a coin being skilfully dropped from different selected points in the slot against the pin selected to obtain a predetermined rebound therefrom, partitions 30 forming pockets to receive coins at the bottom of the passage, a movable bottom for the pockets, and a till into which the coins fall when said bottom is moved.
- 35 4. In a machine of the character described, a cabinet having a glass front, a back carrying pins set in predetermined relationship, said back and front forming between them a coin passage way, a plurality 40 of separate coin receiving pockets disposed at the bottom of the passage way, and a top cover for said passage way having therein a slot which directly overhangs the major portion of the bottom of the passage way 45 above said pockets and is made many times the width of the coin intended to be dropped therethrough to permit a coin to be dropped directly from different points in the slot toward the different pockets, said pins being 50 arranged to prevent the coin being dropped directly into any given pocket, substantially as described.
5. In an apparatus of the character described, a cabinet comprising walls forming 55 a wide vertical coin passage, one wall being transparent, coin deflecting means in said passage, and a cover over said passage provided with a slot extending substantially the width of the passage and having its marginal side edges formed of glass.
6. In an apparatus of the character described, a cabinet provided with a wide ver-
- tically disposed coin passage having its front wall transparent, a series of partitions at the bottom of said passage subdividing 65 it into pockets, resilient members disposed at the upper end of said partitions, rubber covered pins disposed in the passage above said intermediate pockets, a block overhanging each end coin pocket and having inclined top and bottom walls, a resilient member at the apex of each block, a movable bottom for the coin pockets and a till to receive the coins from the pockets, the central and the two end pockets constituting 70 premium giving pockets and being so designated, said pins and blocks being disposed to prevent a coin being dropped directly into any one of said premium giving pockets, and said cabinet having an elongated 80 coin slot at the upper end of said coin passage, which slot extends over the several pins and resilient members, substantially as described.
7. In an apparatus of the character described, a cabinet having a till, a coin passage disposed vertically above said till, a glass front for said passage, vertical partitions which divide the bottom of the passage into coin pockets, resilient members at 90 the upper ends of the partitions, a rubber covered pin disposed centrally above and adjacent to the middle pocket, a similar pin above each pocket next to the middle pocket, an inclined deflector disposed over each end 95 pocket, resilient members at the inner ends of said deflectors, and a rubber covered pin disposed above and in a vertical line between the resilient member of each deflector and the pin over the adjacent intermediate 100 pocket, said cabinet having a coin slot at the top of said passage which extends over said several pins, substantially as described.
8. In an apparatus of the character described, a cabinet having a coin passage, a 105 glass front for said passage, a series of partitions which subdivide the lower end of the passage into coin pockets, rubber tips at the upper ends of said partitions, deflecting means over the side pockets, and a set of 110 pins covered with resilient cushions arranged substantially as shown above the pockets, said cabinet having an elongated coin slot at the upper end of the coin passage which permits the operator to select 115 the pin which he wishes the coin to engage before falling into a pocket, substantially as described.
